CATALOG BINDER

Samuel Segal, New York, N. Y., assignor to Wilson-Jones Co., Chicago, Ill., a corporation of Massachusetts

Application March 30, 1948, Serial No. 18,030

3 Claims. (Cl. 129—1)

1

The subject matter of this invention is an improved and simplified catalog binder featuring the use of separable and complementary members carrying a plurality of transversely arranged and spaced pins adapted to be conveniently threaded into perforations in the catalog or book removably and in part straddled by the complementary members. The principal feature of the improved catalog binder is predicated upon the complementary members being equipped with novel and conveniently controlled primary locking means to preclude accidental and longitudinal displacement of the members relative to each other when arranged in operative relation appropriately straddling the catalog. More specifically however another object and principal feature of the invention is realized in the provision of appropriately accessible detent means carried by one of the complementary members or carrier means. The detent means comprises a flexible and resilient normally curved or arched manipulatable notched portion adapted to be flexed towards a side wall of the carrier means and subsequently automatically but disengageably interlocked with an exposed rib or projection extending from keeper means or companion complementary member of the binder upon slidable displacement of the carrier means longitudinally of the keeper means. Manifestly the primary purpose of the invention resides in the provision of a functionally and structurally improved catalog binder wherein the complementary and cooperating members, namely, the keeper means and carrier means thereof, are adequately latched by primary and secondary separable locking means to preclude longitudinal and transverse displacement of the complementary members relative to each other. Another important feature of the invention is predicated upon a yoke or supporting means effectively straddling and slidably guided on a slotted wall of the carrier means. The yoke has pin means adapted to be initially threaded into and desirably interlocked with both the catalog and keeper means to prevent linear displacement of the supporting means relative to the keeper means. The keeper means has spaced undercut pin means or posts on which the catalog is positioned, whereby upon slidable displacement of the carrier means relative to the posts of the keeper means and to the supporting means, these posts are first removably interlocked with the slotted wall to prevent widthwise separation of the carrier means and keeper means after which the primary locking means is automatically rendered effective to preclude longi-

2

tudinal displacement of the keeper means and carrier means relative to each other. Other important features and advantages of the invention will become more apparent from the following detailed specification considered with the teachings of the accompanying drawings wherein:

Fig. 1 is a perspective view of a catalog binder according to my invention detachably mounted on a suitable support or platform.

Fig. 1A is a side elevational view of the catalog or book to be bound.

Fig. 2 is a longitudinal sectional view on the line 2—2 of Fig. 1.

Fig. 3 is a plan view of Fig. 1.

Fig. 4 is a perspective view of the binder showing the complementary members or components thereof locked by primary means against longitudinal displacement relative to each other.

Fig. 5 is a view similar to Fig. 4 however showing the primary locking means unlatched or disabled to permit lengthwise displacement of one of the complementary members relative to the companion member.

Fig. 6 is a view along the lines of Fig. 5 exhibiting one of the complementary members shifted longitudinally relative to the other for rendering ineffective the secondary locking means to permit lateral separation of the complementary members.

Fig. 7 is a perspective exploded view of the binder showing the complementary members separated.

Fig. 8 is a sectional and enlarged view on the line 8—8 of Fig. 4.

Fig. 9 is a fragmentary plan view of Fig. 4 but on a larger scale.

Fig. 9A is an enlarged fragmentary top view of Fig. 5.

Fig. 10 is a vertical end view of Fig. 9.

Fig. 10A is an elevational end view of Fig. 9A, and

Fig. 11 is an enlarged and fragmentary view illustrating the manner of locking the parts of the complementary members against lateral and relative displacement, that is, by the grooved post means of the keeper removably interlocking with the side wall of the slidable carrier means.

Illustrative of the embodiment disclosed, the catalog binder CB is characterized by the complementary and disconnectable components or members broadly denoted K and S each constituting an L or channel shaped body of appropriate sheet metal. More specifically complementary member K may be said as characterizing keeper means embodying a rectilinear bot-

tom wall 10 integrally provided with turned over lips or guard means 11 and 12 adequately bent to be disposed parallel to bottom wall 10 to constitute therewith gaps 13 and 14 (Fig. 2) respectively for readily receiving and slidably guiding the bottom straight wall 15 of the L shaped component or carrier means S having the upstanding wall or side 16 provided with the compound and spaced openings or slots 17 each comprising an expanded portion 18 and a communicating reduced rectilinear portion 19.

Enlarged openings 18 of the compound slots 17 are large enough to easily receive the free ends of the undercut or grooved posts or pins 20 fixedly anchored to side 21 normal to the bottom wall 10 and integral therewith.

Where the bottom wall 15 is received within the guide channels 13 and 14 to bear against the curved but closed end or stop 22 common to the bottom wall 10 and its turned over retaining lip 12, bottom wall 15 is slidably retained and guided by the guarding lips 11 and 12 in the movement of the slidable component or carrier means S towards wall 21 of the keeper K to permit the free ends of pins 20 to be received and projected into the enlarged or expanded portions 18. Such projection is limited when wall 15 strikes side wall 21, which constitutes a stop. When the free edge of wall 15 is in engagement with side wall 21 the grooves 23 of the spaced pins 20 are disposed in line with the spaced rectilinear walls of the reduced portions 19 and are in position to be straddled thereby.

With the wall 15 within gaps 13 and 14 and against the stop means 22, the spaced compound slots 24 thereof are not in full registration (Fig. 6) with correspondingly shaped compound slots 25 in the bottom wall 10. These compound slots 24 and 25 are each of the type comprising an enlarged opening and a reduced and communicating rectilinear opening along the lines of the compound slots 17. But since the reduced portions 28 of pins 20 formed by providing grooves 23 are now lined up with the restricted openings 19, component S may be slidably guided longitudinally relative to keeper K and towards gap 13 until it strikes the stop means 27 (Fig. 2) integral with lip 11 and the bottom wall 15 and formed when lip 11 is bent and turned towards this wall. When wall 15 strikes stop means 27 compound slots 24 and 25 are in complete registration with each other.

In bodily sliding towards the closed end 27 of gap 13, spaced side walls 26 of grooves 23 straddle and interlock with portions of side wall 16 adjacent openings 19, thus slidably interlocking therewith to prevent separation of component S widthwise or transversely of the bottom wall 10 of the keeper K, and when the closed ends 29 of openings 19 strike the reduced portions 28 of pins 20, compound slots 24 and 25 are fully in registration coincident with end 30 of wall 15 striking the closed end or stop 27 (Fig. 3).

Although the complementary members K and S are now removably locked against widthwise or lateral separation relative to each other, component S may still be slidably guided longitudinally relative to keeper K by the spaced shoulders or faces 26 of the pins 20. To preclude such longitudinal displacement novel locking means has been provided. For purposes of specification this locking means has been designated as the primary locking means. To this end it will be observed that a normally curved or

arched but relatively flat spring detent preferably of appropriate sheet metal adequately flexible and resilient, and generally designated D, has one end 34 fixedly anchored by rivet 35 to side wall 16. The other end M of this spring detent normally curves away from wall 16 (Fig. 9) and constitutes a finger manipulatable portion having tooth T and notch 36.

Concerning lip 12, it will be observed that stop 22 thereof is partly cut away to leave an exposed portion 22' which in fact constitutes an upstanding rib receivable in notch 36 to interlock with the walls of the latter when component or carrier means S is slidably shifted towards lip 11. This locking action takes place automatically after grooves 23 (Fig. 7) of posts 20 are lined up with the reduced openings 19. On shifting of component S in a direction towards lip 11 the upstanding side face 40 of rib 22' characterizes an abutment to deflect and straighten out tooth T of the flexible and resilient manipulator M towards side wall 16 until notch or recess 36 lines up with the rib or exposed portion 22', at which time manipulator M automatically retracts or recoils to its normal offset or arched position to interlock with the exposed rib 22'. Such retraction of manipulator M of course is due to its own resiliency, thus preventing longitudinal displacement of component S relative to the keeper K, and at this time of course compound slots 24 and 25 are in full registration.

Appropriately associated with component S is the self locating supporting member or yoke Y which is of inverted U shaped form having its sides closely but slidably straddling side wall 16. Side wall 16 is provided with a relatively elongated slot 50 slidably guiding pin 51 fixedly carried by the yoke Y. The end walls of slot 50 coact to limit longitudinal displacement of pin 51 relative to side 16. Or in other words pin 51 and the end walls of slot 50 cooperate to limit slidable displacement of the yoke or carrier Y.

If it be assumed that the binder be empty of the catalog or book C and is separated or disassociated as illustrated in Fig. 7, and it is desired to bind the catalog, the first step is to position the keeper K so that its side wall 21 is preferably seated on a suitable support so that wall 10 is disposed substantially vertically. Thereafter the perforated catalog is threaded on the spaced posts 20, that is, the latter is caused to project through the end openings 52 (Fig. 1A) of the catalog C.

Subsequently component or carrier S is bodily moved to permit pin 51 to ride into the middle opening 53 (Fig. 1A) of the catalog and also to project into opening 54 (Figs. 5 and 7) in wall 21 of keeper K at which time the pins or posts 20 are received by enlarged portions 18 of slots 17. By such action pin 51 is interlocked with the keeper K and the circumferential grooves 23 of pins 20 are disposed in alignment with the reduced portions 19 of slots 17. Now component S may be slidably moved relative to both yoke Y and keeper K, whereby spaced shoulders 26 constituted by grooves 23 straddle and interlock with portions of side wall 16 adjacent openings 19. In other words, wall 16 is retained in grooves 23 and interlocked with the spaced walls 26 thereof. On such slidable displacement tooth T of the manipulatable portion M yieldingly bears against the abutting end face 40 of the stop means 22', thereby causing

portion M to flex towards wall 16, and eventually notch 36 alines with rib 22' again allowing automatic retraction of manipulator M. When notch 36 is alined with rib 22' the manipulator M snaps back or recoils, whereby the spaced walls of notch 36 straddle and interlock with rib 22', thus preventing longitudinal displacement of the components relative to each other.

Since carrier S may be slidably adjusted relative to the yoke or supporting means Y, the position of the middle perforations 53 in the catalog C may be varied and consequently the herein disclosed construction is not dependent on a predetermined position of such middle opening.

It is apparent therefore the primary locking means constituted by detent D in association with rib 22' prevents relative longitudinal displacement of the components K and S while the secondary or supplementary locking means defined by the reduced portions 19 of slots 17 in cooperation with the pins 20 preclude widthwise relative displacement of these components. The secondary locking means may be rendered ineffective only after the primary locking means has been disabled. The disablement of the primary locking means takes place upon shifting manipulator M by finger pressure towards side 16 to clear rib 22', thereby permitting component S to be shifted relative to keeper K, consequently moving the reduced portions 19 of slots 17 free of pins 20 which are now arranged in the enlarged portions 18 to allow removal of component S from the pins 20. From the foregoing description it is obvious that components S and K, when desired, may be quickly separated to permit removal of the catalog in part or whole from the binder or for replacement of the old catalog by a new one into the binder.

As previously stated when the components K and S are latched together by the primary and supplementary locking means, compound slots 24 and 25 are fully in registration (Figs. 3 and 9) and locking pin 51 of yoke Y is removably interlocked with wall 21. The catalog is therefore arranged between keeper K and carrier S and on pins 20 and 51 and is now appropriately bound. Since slots 24 and 25 are in full registration at this time, the binder CB may be quickly removably locked to a pair of spaced posts as 60 and 61 fixed to the inclined platform or support 62 of the stand 63.

However posts 60 and 61 are undercut to provide reduced portions 64 to permit their reception in the reduced parts 65 of the alined slots 24 and 25 (Figs. 2 and 9) to prevent widthwise displacement of the binder CB relative to stand 63. Enlarged heads 66' of posts 60 and 61 cooperative to effectively hold binder to the stand, that is, to prevent upward removal of the binder from these posts when heads 66' are over the reduced parts 65 of slots 24 and 25. By moving the binder towards the right (Figs. 2 and 3) enlarged portions of slots 24 and 25 receive the heads 66' and unlock from posts 60 and 61 permitting withdrawal of the binder therefrom, since these enlarged portions are larger than heads 66'.

If desired, covers CC (Fig. 1) may be removably mounted on the stand 63 which embodies spaced openings 70 for receiving laterally extending lugs 71 defining obtuse angles with the body of the covers and cooperating with platform or wall 62 for retaining the covers on the stand and inclined thereto as illustrated in Fig. 1.

Various changes may be made in details of construction and arrangement of parts without departing from the spirit of the invention or sacrificing any of the advantages thereof inherent therein.

I claim:

15. 1. In a binder, supporting means, a carrier slidably guided by said supporting means and having a slot, a pin fixed to said supporting means and projecting through said slot, a member having an opening for removably receiving said pin to prevent shifting of said supporting means relative to said member, and disengageable locking means on said carrier and member and effective upon slidable displacement of said carrier relative to said supporting means when said pin is within said opening to preclude shifting of said carrier longitudinally of said member.
20. 2. In a binder, supporting means, a carrier slidably guided by said supporting means and having a slot, a pin fixed to said supporting means and projecting through said slot, a member having an opening for removably receiving said pin to prevent shifting of said supporting means relative to said member, disengageable locking means on said carrier and member and effective upon slidable displacement of said carrier relative to said supporting means when said pin is within said opening to preclude shifting of said carrier longitudinally of said member, and disengageable locking means to prevent widthwise displacement
25. 3. In a binder, supporting means, an L shaped carrier having a wall closely straddled and slidably guided by said supporting means and including an elongated slot having end portions, a pin fixed to said supporting means and projecting through said slot and cooperating with said end portions to limit longitudinal displacement of said carrier, a keeper having a side wall including an opening for removably receiving said pin to prevent shifting of said supporting means relative to said keeper, and disengageable locking means on said carrier and keeper and effective upon slidable displacement of said carrier relative to said supporting means when said pin is within said opening to preclude shifting of said carrier longitudinally of said keeper.

SAMUEL SEGAL.
